UNITED STATES PATENT OFFICE.

JOHN H. HUNT, OF DAYTON, OHIO, ASSIGNOR, BY MESNE ASSIGNMENTS, TO DELCO-LIGHT COMPANY, OF DAYTON, OHIO, A CORPORATION OF DELAWARE.

IGNITION SYSTEM.

Application filed April 10, 1919. Serial No. 288,938.

To all whom it may concern:

Be it known that I, JOHN H. HUNT, a citizen of the United States of America, residing at Dayton, county of Montgomery, 5 State of Ohio, have invented certain new and useful Improvements in Ignition Systems, of which the following is a full, clear, and exact description.

This invention relates to ignition systems 10 for internal combustion engines and has among its objects the provision of ignition particularly for power plants including an electric generator driven by an internal combustion engine but where a storage battery for accumulating all or part of the output of the plant is not necessarily included as part of the power plant equipment.

A further object is to provide ignition for power plants of the kind described, in which 20 the voltage of the generator is considerably higher relatively to that employed in the usual battery type ignition system. In carrying out this object it is an aim of the invention to provide means by which the high 25 voltage current of the generator can be used in connection with an ignition coil which is standard with respect to ignition systems operating at relatively low voltage.

Other and further objects of the present 30 invention will be apparent from the following description, reference being had to the accompanying drawing, wherein a preferred form of one embodiment of the present invention is clearly shown.

35 In the drawing:

Fig. 1 is a diagrammatic side elevation of an engine, partly in section, together with a wiring diagram illustrating one form of the invention.

40 Fig. 2 shows a modified form of the automatic control.

In the drawing, an engine 20 is provided with a crank shaft 21 driven by piston 22 through connecting rod 23. Crank shaft 21 carries fly-wheel 24, timer gear 25, generator armature 26 and commutator 27. Armature 26 cooperates with generator field 28 to induce current in armature windings which is conducted through brushes 29 and 30 and wires 31 and 32 to terminals 33 and 34, respectively. Terminals 33 and 34 may be connected by suitable switches with work circuits not shown.

Timer gear 25 cooperates with timer

gear 35 to drive timer cam shaft 36 carrying 55 timer cam 37. Cam 37 is provided with a dwell measured by the angle XOY, in direction of rotation indicated by arrow 38, and with a depression or valley measured by angle YOX. Cam 37 cooperates with 60 breaker lever 39 pivotally mounted on timer housing 40 and carrying contact 41 which cooperates with contact 42 mounted on housing 40 but insulated therefrom. Spring 43 maintains contacts 41 and 42 in engagement during the closing period of the primary ignition circuit which will now be described.

Wire 44 connects contact 42 with ignition coil primary winding 45 which is connected 70 with switch 46, resistance 47 and wire 31. Contact 41 is connected through lever 39 and timer housing 40 with wire 47^a which is connected with switch contact 48. Switch lever 49 is arranged to connect contact 48 75 with contacts 50 or contact 51. Contact 50 is connected with a battery 52 which is connected with ignition switch 46. Contact 51 is connected with wire 32. Switch lever 49 may be operated manually, but is preferably 80 controlled by a centrifugal device comprising a shaft 53 journaled on the engine frame, and carrying a wheel 54 in frictional engagement with the flywheel 24. Wheel 54 supports pivotally mounted weight elements 85 55 which are connected by links 56 with a grooved collar 57 slidably mounted on shaft 53. Collar 57 is engaged by stud 58 mounted on lever 49. A spring 59 interposed between wheel 54 and collar 57 tends to resist 90 the movement of weights 55 which move outwardly after the engine attains a predetermined speed due to centrifugal force.

A condenser 60 is connected in parallel 95 with the timer contacts.

Ignition coil secondary winding 61 is grounded and connected with spark plug 62.

The operation of the invention is as follows:

When the engine is at rest, switch lever 49 100 is in position shown in the drawing. By closing switch 46 the battery 52 is connected in series with the coil 45 and the timer. The crank shaft 21 is revolved manually or by a starting device, not shown. The primary 105 circuit is made when axis OX of cam 37 is in the position shown, and is broken when axis OY turns into the position occupied by

axis OX in the drawing. The battery voltage and transformation ratio of the ignition coil is such that no spark will occur on the make but only on the break of the primary circuit when battery current is used. The axis OY is so timed that the break will occur at the proper time for retarded ignition desired on starting the engine.

When the engine has become self operative and has attained a predetermined speed such that the generator is producing current sufficient for ignition purposes, lever 49 is moved automatically into engagement with contact 51 to complete the ignition circuit through the generator and to disconnect the battery 52. The generator voltage is such with relation to the transformation ratio of the ignition coil that a spark will occur on the "make" of the primary circuit, that is, when cam axis OX is in the position shown in the drawing. Axis OX is timed so as to give the proper spark advance for the normal running operation of the engine. The spark which subsequently occurs as the break will 25 do no harm since the combustible mixture has already been exploded.

The present invention therefore provides ignition for power plants including a generator driven by an internal combustion engine but where a storage battery for the accumulation of part or all of the plant output is not necessarily included in the plant equipment. The battery 52 may consist of a few dry cells or may be a small storage battery. In either case, since battery 52 is used for starting ignition only, it may be comparatively small in size. Therefore it is apparent that the power plant described may be used advantageously where power is to be used direct and no storage of power is required. Such a plant may be made very portable, adapting it for outdoor construction work where power for operating lamps and motors and the like is required.

The present invention is advantageous in that a standard low voltage ignition coil can be used with a comparatively high voltage generator, for example one delivering current at 110 volts. This is important from a manufacturing point of view since it is possible to provide a standard coil for a series of power plants furnishing current at different voltages.

A further advantage of the invention results from its simplicity of control, there being but one manual switch which is closed on starting the engine, and opened to stop the engine. The change over from battery to generator and the advance of the ignition timing is effected automatically so that nothing is left to the memory or skill of the user.

The switch lever 49 can be controlled in accordance with the speed or operation of the engine in other ways than through the agency of a centrifugal device. For ex-

ample, as is shown in Fig. 2, switch lever 49 can be normally held in engagement with contact 50 by a spring 70. An electromagnet 71 connected across the leads 31 and 32 is arranged to cooperate with armature 72 which is connected to lever 49 so that at a predetermined voltage corresponding to a predetermined engine speed, the lever 49 will be moved by magnetic attraction into engagement with contact 51. In both forms of the invention the switch lever 49 is controlled by the speed of the engine either directly by the centrifugal device or indirectly through the agency of an electromagnetic device.

While the form of mechanism herein shown and described constitutes a preferred embodiment of one form of the invention, it is to be understood that other forms might be adopted, and various changes and alterations made in the shape, size and proportion of the elements therein without departing from the spirit and scope of the invention.

I claim—

1. In an ignition system, the combination with an engine; of a relatively low voltage current source; a relatively high voltage current source; an ignition coil arranged to provide a spark at the instant of connection with the high voltage source, or a spark at the instant of break of connection with the low voltage source; a timer arranged to time the make of the ignition circuit at the proper advance for engine running, and to time the break of the ignition circuit at the proper retard for engine starting; and means for connecting either current source with the ignition coil and timer.

2. In an ignition system, the combination with an engine; of a relatively low voltage current source; a relatively high voltage current source; an ignition coil arranged to provide a spark at the instant of connection with the high voltage source, or a spark at the instant of break of connection with the low voltage source; a timer arranged to time the make of the ignition circuit at the proper advance for engine running, and to time the break of the ignition circuit at the proper retard for engine starting; and means for connecting either current source with the ignition coil and timer, said means being controlled by the speed of the engine.

3. In an ignition system, the combination with an engine; of a relatively high voltage generator driven thereby; of a relatively low voltage and independent current source; an ignition coil arranged to provide a spark at the instant of connection with the generator, or a spark at the instant of break of connection with the low voltage source; a timer arranged to time the make of the ignition circuit at the proper advance for engine running, and to time the break of the ignition circuit at the proper retard for en-

- gine starting; and means for connecting either current source with the ignition coil and timer.
4. In an ignition system, the combination with an engine; of a relatively high voltage generator driven thereby; of a relatively low voltage and independent current source; an ignition coil arranged to provide a spark at the instant of connection with the generator, or a spark at the instant of break of connection with the low voltage source; a timer arranged to time the make of the ignition circuit at the proper advance for engine running, and to time the break of the ignition circuit at the proper retard for engine starting; and means for connecting either current source with the ignition coil and timer, said means being controlled by the speed of the engine.
5. In an ignition system, the combination with an engine; of a plurality of current sources; an ignition coil adapted to produce a spark at the instant of connection with one source, and adapted to produce a spark at the instant of disconnection from the other source; a timer arranged to effect the said disconnection at the proper time for engine starting, and to effect the said connection at the proper time for engine running; and means for connecting either current source with the coil and timer.
6. In an ignition system, the combination with an engine; of a plurality of current sources; an ignition coil adapted to produce a spark at the instant of connection with one source, and adapted to produce a spark at the instant of disconnection from the other source; a timer including cooperating contacts connected in the primary circuit of said coil, a breaker lever carrying one of the contacts, and an engine driven cam cooperating with said breaker lever, said cam being arranged to permit the contacts to close at the proper instant for sparking during engine running conditions and to cause the contacts to separate at the proper instant for sparking during engine starting conditions; and means for connecting either current source with the coil and timer.
7. In an ignition system, the combination with an engine; of an ignition coil; a timer connected with the ignition coil; a low voltage current source; a high voltage current source; means for connecting either of said

sources with the ignition coil and timer; the low voltage source being of such voltage as to produce a spark only upon the break of the timer and the high voltage source being of such voltage as to produce a spark on the make of the timer.

8. In an ignition system, the combination with an engine; of ignition means including a circuit, an ignition coil connected therewith, and a timer operating in fixed relation to the engine cycle and adapted to actuate timer contacts to make and break said circuit at different points in the engine cycle; a current source adapted when connected with said circuit to cause engine ignition only at the break of said circuit; and a second current source adapted when connected with said circuit to cause engine ignition at the make of said circuit.

9. In an ignition system, the combination with an engine; of ignition means including a circuit, an ignition coil connected therewith, and a timer operating in fixed relation to the engine cycle and adapted to actuate timer contacts to make and break said circuit at different points in the engine cycle, said ignition means adapted when operated at one voltage to cause engine ignition only at the break of said circuit and when operated at another voltage to cause engine ignition at the make of said circuit; and means for impressing different voltages on said ignition means.

10. In an ignition system, the combination with an engine; of ignition means including a circuit, an ignition coil connected therewith, and a timer operating in fixed relation to the engine cycle and adapted to actuate timer contacts to make and break said circuit at different points in the engine cycle, said ignition means adapted when operated at one voltage to cause engine ignition only at the break of said circuit and when operated at another voltage to cause engine ignition at the make of said circuit; and means responsive to engine speed for impressing different voltages on said ignition means.

In testimony whereof I affix my signature.

JOHN H. HUNT.
